PENDANT DRIP RECEPTACLE FOR HANGING POTTED PLANTS

Del G. Connell, 22915 Dolorosa St.,
Woodland Hills, Calif. 91364

Filed June 30, 1975, Ser. No. 591,621

Term of patent 14 years

Int. Cl. D11—02

U.S. Cl. D6—113

FIG. 1 is a perspective view of a pendant drip receptacle for hanging potted plants, showing my new design;

FIG. 2 is a top plan view thereof; and

FIG. 3 is a side elevation as viewed from the top or bottom in FIG. 2.

I claim:

The ornamental design for a pendant drip receptacle for hanging potted plants, as shown.
